Attorney

UNITED STATES PATENT OFFICE.

MABEL IOLA McCONKEY, OF CHICAGO, ILLINOIS.

DESIGN FOR AN INCENSE BURNER.

•60,798.

Specification for Design.

Patented Apr. 11, 1922.

Application filed November 12, 1921. Serial No. 514,798. Term of patent 3½ years.

To all whom it may concern:

Be it known that I, MABEL IOLA McCONKEY, a citizen of the United States of America, residing at Chicago, in the county of Cook and State of Illinois, have invented a new, original, and ornamental Design for an Incense Burner, of which the following is a specification, reference being had to the accompanying drawing, forming part thereof.

The figure is a perspective view of an incense burner showing my new design.

I claim:

The ornamental design for an incense burner as shown.

MABEL IOLA McCONKEY.

Witnesses:

A. F. McCONKEY,
LEONA M. WACKROW.
